(57) **CLAIM**

The ornamental design for an interlocking container, as shown and described.

DESCRIPTION

FIG. 1 is a perspective view of an interlocking container showing our new design;

FIG. 2 is a top plan view thereof;

FIG. 3 is a bottom plan view thereof;

FIG. 4 is a side elevation view thereof, the side opposite being identical; and,

FIG. 5 is an end elevation view thereof, the end opposite being identical.
